UNITED STATES PATENT OFFICE.

FRED FRANKE, JAMES E. MILLER, AND ELDER E. ROBERTS, OF LOUISVILLE, KENTUCKY, ASSIGNORS, BY MESNE ASSIGNMENTS, TO FRED FRANKE & COMPANY, A CORPORATION OF KENTUCKY.

MATTRESS CLEANING, MIXING, OPENING, AND FILLING MACHINE.

Application filed October 22, 1921. Serial No. 509,521.

To all whom it may concern:

Be it known that we, FRED FRANKE, JAMES E. MILLER, and ELDER E. ROBERTS, citizens of the United States, residing at Louisville, in the county of Jefferson and State of Kentucky, have invented certain new and useful Improvements in Mattress Cleaning, Mixing, Opening, and Filling Machines, of which the following is a specification, reference being had to the accompanying drawings.

This invention relates to machines used in the making of mattresses, and particularly to machines for cleaning, opening and mixing cotton, cotton wastes, kapok, feathers, and similar materials used in the manufacture of mattresses.

The general object of the invention is to provide a machine of this character which shall open and thoroughly pick the material of which the mattress is to be made and which will remove the dust and dirt therefrom, and in which the amount of dust and dirt to be taken out of the material can be regulated, thus obviating the objection incident to many machines intended for the same purpose that the stock is either not properly cleaned or too much good stock is lost.

A further object in this connection is to provide means whereby when the stock is opened up, the heavy dirt, seeds and like relatively heavy foreign matter will drop downward through a wire screen, while at the same time the light and fine dust is being drawn through a screen in the upper portion of the beating compartment, and the provision of means whereby the amount of relatively heavy foreign matter removed from the mattress material and the amount of relatively light dust removed from the mattress material can be independently regulated or indeed shut off entirely.

Another object is to provide a construction of this kind which will remove most, if not all, of the light fine dust, not only making a much better mattress but improving the condition of the workroom.

Still another object is to provide a machine of this character in which the mattress material or stock may be fed into a beater or picker chamber at one end thereof, will be carried around and around in a spiral course within the beater while being

thoroughly picked apart and the dust and foreign matter removed therefrom, and is then removed by suction from the picking or beating chamber and blown directly into the mattress or pad in which it is to be used.

Other objects will appear in the course of the following description.

Our invention is illustrated in the accompanying drawings, wherein:

Figure 1 is a top plan view of a mattress stock picker and cleaner constructed in accordance with our invention;

Figure 2 is a section on the line 2—2 of Figure 1;

Figure 3 is a longitudinal section on the line 3—3 of Figure 2;

Figure 4 is an end elevation of the machine;

Figure 5 is a perspective view of the machine;

Figure 6 is a detail fragmentary view of the locking means for one of the chains.

Referring particularly to Figures 1 and 5, it will be seen that this machine includes an outer, rectangular casing, designated generally 10, and through which passes the beater shaft 11 mounted in suitable bearings in the ends of the casing. This shaft 11 at one end carries the fast and loose pulleys 12 and 13 whereby power is adapted to be applied from a belt to the beater shaft and thus to the other instrumentalities of the machine. At its opposite end, the shaft 11 carries upon it the pulley 14. Mounted upon the beater shaft or picker shaft are a plurality of beater arms 15 which extend radially through the shaft and may be of different lengths and are arranged spirally around the shaft so that these beater arms or pickers not only act as beaters and pickers but they also act in a sense as a screw conveyor tending to cause the travel of the stock from one end of the beater chamber to the other. The bottom of the beater cylinder is formed by a screen of relatively coarse mesh and designated 16, which is attached by cleats or other means to the side walls of the beater chamber, and hingedly mounted upon the side walls of the beater chamber are two valves or doors 17 and 18 which constitute dirt discharge regulators. These doors are formed of sheet metal initially flat but yielding as they are drawn to a closed position so that they will

70

95

100

105

closely approximate the shape of the curved screen 16. When these doors are pulled up they will first engage against the screen on the extreme outer margins of the doors, 5 then the middle of the doors will engage as they are more tightly closed, and eventually the whole door will fit tightly against the screen. It will be seen that if one of these doors is closed, one-half of the screen surface is closed, and that if only the outer margins of the doors contact with the screen that only a portion of the screen will permit the passage of dirt. This screen 16 is 10 of sufficiently large mesh to allow all of the dirt to be knocked out of the mattress material while it is passing through the machine if the doors 17 and 18 are fully opened. The screen 16, and these doors are capable of being drawn up into relatively close contiguity to the screen or allowed to open out 15 to any desired degree.

To the end that the doors may be shifted to regulate the discharge of dirt therefrom chains 19 are attached to the free edges of the doors and extend from the free edge to 20 the opposite side wall of the casing and through an opening 20 in this side wall. A plate 21 is attached over this opening which is provided with a slot, as for instance a 25 keyhole slot, 22 which permits the chains to be held in any adjusted position. It will be obvious that by lifting the chain up, it may be pulled or released to shift the door, and that by bringing the chain down within the narrow 30 portion of the keyhole slot, the links will catch on the wall of the keyhole slot and hold the door in its adjusted position. Any other means may be used for holding these chains with the doors in adjusted position. 35 The lower portion of the casing 10 below the doors 17 and 18 forms a receptacle into which the dirt, seeds and other heavy foreign matter which falls downward through the screen may be received.

40 Extending over the beater are a plurality of angle irons 23 which support plates 24 extending upward toward each side of the beater from the middle thereof, and disposed between these plates and arching over the middle of the space between the edges of the plates is the screen 25 of fine mesh. The plates 24 and the angle irons 23 carry upon them a plurality of longitudinally extending saws 26 or combs which act to thoroughly 45 comb out the stock as it is whirled around by the beaters and also act to retard the movement of the stock from the entrance end of the beater chamber to the discharge end thereof. We have illustrated these combs as 50 in the form of saws having teeth beveled from the inlet end of the machine, but we do not wish to be limited to this.

Extending inward from the side wall of the machine is a shelf or board 27, and hingedly mounted adjacent the edge of this board

is a cover section 28 and hingedly mounted to this first cover is a second cover section 29. These cover sections may be extended over the screen 25, as illustrated in dotted lines in Figure 3, or turned back so that the 70 cover section 28 is disposed over the board 27, and the cover section 29 extends partly over the screen or the cover section 29 may be turned up to an approximately vertical position so as to carry it entirely away from 75 the screen. These cover sections 28 and 29 form doors whereby the amount of dust which is taken from the stock may be regulated and controlled.

The door sections 28 and 29 permit either 80 the whole or a portion of the upper screen 25 to be closed and this will control the amount of light dust which is drawn off into the casing which extends over the screen 25.

The casing 10 has a length somewhat greater 85 than that of the beater and extends up above the cover sections 28 and 29, as illustrated in Figure 2, the front of this casing being provided with a hinged door 30 whereby access may be had to the interior of the 90 upper portion of the casing. The lower portion of the casing may be also provided with a removable door whereby access may be had to the lower portion of the casing if desired.

One end of the casing is formed with an 95 inlet opening 31, and extending out from this inlet opening are brackets 32 upon which a feed belt is mounted whereby stock may be fed into the beating chamber. Carried at the inner end of these brackets is a transversely extending shaft 33 which projects 100 out at both ends beyond the brackets, and disposed at the outer ends of the brackets are the longitudinally adjustable slides 34 which carry the shaft 35 supporting a roller 105 36. The shaft 33 carries upon it a roller 37 and over these rollers travels the transversely slatted conveyor belt 38. The slides 34 are longitudinally slotted and held in place by means of a bolt having the wing nut 39 110 and these slides are adjusted by means of the adjusting screws 40 having screw-threaded engagement with the bracket at the rear end of the slots 41 in which the slides move. Thus the tension of the conveyor belt 38 may 115 be taken up from time to time.

At the inner end of the brackets is also mounted the feed roller 42 mounted upon a shaft 43. The shaft 33 carries loose upon it at one end the relatively large sprocket 120 wheel 44 which is driven by means of the sprocket chain 45 from the sprocket wheel 46 mounted upon a transverse shaft 47 also mounted in the brackets and carrying a band wheel 48 which is driven by a belt 49 from a 125 relatively small band wheel 50 mounted upon the beater shaft 11. This shaft 47 also carries upon it a gear wheel 54 which meshes with a gear wheel 55 on a transverse shaft 56 disposed above the shaft 47 and carrying 130

a sprocket wheel 57 over which a sprocket chain 58 runs to a sprocket wheel 59 mounted upon the shaft 43 of the feed roller. Thus the feed roller and the conveyor belt 38 will 5 be driven at the same speed.

The pressed fiber or other mattress material is placed on the conveyor belt 38 and is carried under the corrugated feed roller 42, this feed being the same as that com- 10 monly used in machines for picking cotton

apart, and from these feed rollers the stock is taken by the revolving beater shaft and carried through the machine by the spirally arranged beater fingers and is combed out 15 by means of the several rows of saw teeth heretofore referred to.

For the purpose of carrying off the light dust, we provide an air duct 60 which extends downward at the rear end of the ma- 20 chine and which may be in the form of a pipe, this duct at its lower end communicating with the fan chamber 61 wherein is dis- posed a suction fan 62 mounted upon a shaft 63, which shaft carries a band wheel 25 64 driven by means of a belt 65 from the main beater shaft 11 of the machine. This fan chamber 61 has a discharge outlet 66. The shaft 63 extends longitudinally of the machine and into a suction fan chamber 67 30 which has a discharge opening 68 and a lateral opening 69 leading into a stock dis- charge box 70 which opens at its upper end into the beater casing at 71. The stock is drawn through the opening 71 into the stock 35 discharge box and drawn downward and into the suction fan casing and is discharged out through the outlet thereof directly into the mattress or pad which is being made. Duct 60 has an adjustable gate 60^a.

40 This gate 60^a controls the draft or suction and is intended to be opened to the amount required in order to remove the proper amount of dust. If it is only partially open it will not permit the removal of as much 45 dust as when fully opened and the entire current of air is being drawn or sucked through the stock.

It will be seen that with this mechanism the mattress material may be cleaned, mixed, 50 thoroughly picked apart and opened and filled into the mattress casing or pad casing, and that while it is being mixed and opened the heavy dirt disengaged from the hairs or fibers will drop downward through the 55 screen 16, while the light dust and foreign particles are drawn out through the screen 25. By providing a feed conveyor with a feed roller, we secure a fine feed of the machine, thus preventing an operator from 60 feeding too much of the stock into the cleaner at one time and thus preventing the material from becoming clogged or packed within the beater chamber. The dust dis- charged by the dust fan may be conveyed to 65 any suitable point of deposit by means of an

ordinary stove pipe. This attachment removes most of the light, fine dust and thus makes a better mattress, and also improves the condition of the work-room. A very important feature of the invention is that the 70 amount of dust and dirt to be taken out from the stock can be regulated, thus while permitting the stock to be thoroughly cleaned, preventing good stock from being lost. 75

Thus when the machine is used for mixing or opening up stock for a Garnett machine or when running clean stock from which there is nothing to be removed, the doors which cover the screens are closed en- 80 tirely. The doors are partially closed when it is not desired to thoroughly clean the stock. Thus a mattress manufacturer will use the same grade cotton for first and second grade mattresses, removing all of 85 the dust to make the better grade mattress but leaving part of the dust and dirt in for the lower grade. The suction pipe is pro- 90 vided with the gate or door 60^a to provide for running different grades of material through the machine. Thus when running a heavy stock the suction pipe is left entirely open, while on the lighter material it is par- 95 tially closed and serves a purpose similar to the doors over the screens. The feeding mechanism is necessary in order that the stock may be gripped while it is being fed into the machine so that the fingers on the shaft will tear the stock up into small pieces, thus opening the stock up more thor- 100oughly. Furthermore, this feeding mecha- 100 nism prevents the operator's arm from being drawn into the machine.

We claim:—

1. A mattress stock cleaning and picking 105 machine comprising a supporting frame, a beater chamber, a beater cylinder therein, the top and bottom of which are formed of fine wire mesh, the beater cylinder having an entrance opening at one end and a dis- 110 charge opening at the other end, a beater shaft passing through the cylinder and having beaters mounted thereon, dust collecting suction means connected to the upper portion of the beater chamber whereby to re- 115 move fine dust from the stock, and adjustable closures coating with the screens to regulate the discharge therethrough.

2. A mattress stock cleaning and picking 120 machine comprising a supporting frame, a beater chamber, a beater cylinder therein, the top and bottom of which are formed of fine wire mesh, the beater cylinder having an entrance opening at one end and a dis- 125 charge opening at the other end, a beater shaft passing through the cylinder and having beaters mounted thereon, dust collecting suction means connected to the upper portion of the beater chamber, and sectional closures coating with the screens and 130

adapted to be adjusted to regulate the discharge therethrough.

3. A mattress stock cleaning and picking machine comprising a supporting frame, a beater chamber, a beater cylinder therein, the top and bottom of which are formed of fine wire mesh, the beater cylinder having an entrance opening at one end and a discharge opening at the other end, a beater 10 shaft passing through the cylinder and having beaters mounted thereon, dust collecting suction means connected to the upper portion of the beater chamber, sectional hinged doors constituting closures coacting with 15 the upper screen to regulate the discharge of dust therethrough, a pair of hinged doors constituting closures coacting with the lower screen and controlling the discharge of dust therethrough, and means extending 20 to the exterior of the casing whereby said lower closures may be adjusted.

4. In a mattress stock cleaner and picker, a cleaning chamber, a cleaning cylinder mounted therein having an entrance at one 25 end and a discharge opening at the opposite end, means for feeding material in at the entrance opening; suction means for withdrawing material from the discharge opening; a longitudinally extending shaft 30 through the cylinder, beater fingers mounted upon the shaft in spirally extending series, longitudinally extending combs mounted at intervals on the wall of the cylinder, screens forming the bottom and top of the beater 35 cylinder, a dirt collecting chamber disposed below the lower screen, a dust collecting suction fan operatively connected to the cleaning chamber above the uppermost screen, and doors coacting with the upper 40 and lower screens to control the effective area of said screens, said doors being adjustable.

5. A picker and cleaner for mattress stock comprising a casing formed to provide a 45 cleaning chamber in the upper portion of the casing, a cleaning cylinder extending lengthwise through the casing, the upper and lower walls of the cleaning cylinder being formed by screens and the cylinder at 50 one end having an entrance opening to the exterior of the casing and at the other end having a discharge opening, a shaft extending through the casing and longitudinally through the cleaning cylinder, beater 55 fingers carried upon said shaft, adjustable doors coacting with said screens to control the effective area of the screens, a longitudinally extending shaft driven from the beater shaft, a fan casing surrounding one 60 end of the shaft and being operatively connected to the discharge opening of the cylinder, a suction fan disposed in said fan casing, a suction fan casing operatively connected to the cleaning chamber above the 65 upper screen, a suction fan mounted upon

said second named shaft and disposed within the casing, means for driving the second named shaft from the first named shaft, and feeding means coacting with the inlet opening of the casing cylinder and driven from 70 said first named shaft.

6. A picker and cleaner for mattress stock comprising a casing formed to provide a cleaning chamber in the upper portion of the casing, a cleaning cylinder extending lengthwise through the casing, the upper and lower walls of the cleaning cylinder being formed by screens and the cylinder at one end having an entrance opening 75 to the exterior of the casing and at the other end having a discharge opening, a shaft extending through the casing and longitudinally through the cleaning cylinder, beater fingers carried upon said shaft, adjustable doors coacting with said screens to control 80 the effective area of the screens, a longitudinally extending shaft driven from the beater shaft, a fan casing surrounding one end of the shaft and being operatively connected to the discharge opening of the cylinder, a suction fan disposed in said fan casing, a suction fan casing operatively connected to the cleaning chamber above the upper screen, a suction fan mounted upon 85 said second named shaft and disposed within the casing, means for driving the second named shaft from the first named shaft, feeding means coacting with the inlet opening of the casing cylinder and driven from 90 said first named shaft, said feeding means including a horizontally disposed endless conveyor, and a corrugated feeding roller disposed above the endless conveyor, the conveyor and the feeding roller being 95 driven at the same speed.

7. A mattress stock cleaning machine including a cleaning chamber having a stock feed opening at one end and a discharge opening at the other end, a foraminous screen extending along and forming part 110 of the wall of said chamber and through which foreign material separated from the stock may be discharged, and doors adapted to partially or wholly close said screened portion of the wall to thereby control the 115 amount of foreign matter discharged through said screen.

8. A mattress stock cleaning mechanism including a cleaning cylinder, a foraminous screen extending along and forming part 120 of the chamber wall, a door of thin, flexible material hinged at one edge adjacent the margin of the screened portion of the wall and adapted to fit against the outside face of the screen, and means for causing 125 the door throughout its whole or part of its surface to conform to and fit against the screen to thereby control the amount of foreign matter passing through the screen.

9. A mattress stock cleaning machine in- 130

- cluding a cleaning cylinder, a foraminous screen extending along the bottom of the cleaning cylinder and forming part of the wall thereof, the screen being outwardly curved to conform to the curvature of the cylinder, a pair of doors of thin, flexible material hinged along their outer edges adjacent the outer edges of the screen, and means engaging the free edges of the doors causing said doors throughout their whole or part of their surface to conform to and fit against the screen to thereby control the amount of foreign matter dropping there-through.
10. A mattress stock cleaning machine including a cleaning cylinder having a feed opening and a discharge opening at opposite ends, the upper and lower walls of the
- cleaning cylinder being formed by screens, a casing extending over the upper portion 20 of the cylinder and over the upper screen, suction means connected to said casing whereby to remove the dust from the stock, the lower screen having a mesh sufficiently coarse to permit the passage of relatively 25 heavy dirt, adjustable doors for controlling the effective area of said screen, a beater disposed within the cleaning cylinder, and means for controlling the amount of suction exerted on the air in the chamber above the 30 upper screen.

In testimony whereof we hereunto affix our signatures.

FRED FRANKE.
JAS. E. MILLER.
ELDER E. ROBERTS.
